US00D703005S

(12) United States Design Patent
Tiemann

(10) Patent No.: US D703,005 S
(45) Date of Patent: * Apr. 22, 2014

(54) DRAWER FOR HOLDING BEVERAGE CARTRIDGES

312/323, 330.1, 334.1, 334.27, 408,
312/410, 334.44; 220/485

See application file for complete search history.

(71) Applicant: Nifty Home Products, Inc., Madison Lake, MN (US)

(72) Inventor: Frank R. Tiemann, Madison Lake, MN (US)

(73) Assignee: Nifty Home Products, Inc., Madison Lake, MN (US)

() Term: 14 Years

(21) Appl. No.: 29/466,309

(22) Filed: Sep. 6, 2013

(51) LOC (10) Cl. 07-06

(57) CLAIM

The ornamental design for a drawer for holding beverage cartridges, as shown and described.

DESCRIPTION

FIG. 1 is a front, right perspective view of the drawer for holding beverage cartridges showing my new design;
FIG. 2 is a front, right perspective view shown open thereof;
FIG. 3 is a top plan view thereof;
FIG. 4 is a front elevational view thereof;
FIG. 5 is a left side elevational view thereof;
FIG. 6 is a rear elevational view thereof;
FIG. 7 is a right side elevational view thereof; and,
FIG. 8 is a bottom plan view thereof.

1 Claim, 5 Drawing Sheets
